DOMESTIC WASHING MACHINE AND
METHOD

Kendall Clark, Oakwood, Ohio, assignor to General Motors Corporation, Dayton, Ohio, a corporation of Delaware

Application May 21, 1943, Serial No. 487,879

9 Claims. (Cl. 8—159)

1

This invention relates to domestic appliances and more particularly to washing machines.

An object of this invention is to provide a washing machine with a scum-removing construction.

Another object of this invention is to provide a washing machine of the centrifugal type, which is provided with a construction which arrests scum during the washing operation and discharges the scum centrifugally during the centrifugal drying operation.

Further objects and advantages of the present invention will be apparent from the following description, reference being had to the accompanying drawing, wherein a preferred form of the present invention is clearly shown.

In the drawing:

The figure is a vertical cross-sectional view of the tub and agitator construction of a washing machine embodying my invention.

My invention is particularly applicable to a washing machine of the centrifugal type. In the embodiment now preferred, the washing machine is provided with an outer, imperforate, liquid-retaining tub 10, which carries an inner perforate tub 11, spaced from the outer tub 10 to provide a space 12 between the tubs. Preferably the inner tub 11 is secured to the outer tub 10 by a rivet construction 13, so that the two tubs rotate, or remain stationary, together. The space 12 is open between the rivets 13, so that liquid may flow from the part of space 12 below rivets 13 to the space 12 above the rivets 13.

Means are provided for agitating the washing fluid and articles to be washed. In the form now preferred, an agitator 14 is carried inside the inner tub 11 and is of such a construction that it produces a toroidal circulation of the washing fluid, and articles to be washed. Preferably, for the washing operation, the tubs 10 and 11 are held stationary, and liquid is introduced into the tubs up to the level 15, together with articles to be washed, which are placed within the inner tub 11. The agitator 14 is then vertically reciprocated at a rapid rate, such as 400 pulsations per minute. The agitator 14 may be provided with a flexible cone 16 at its lower edge, made of rubber or the like, so that the liquid and articles to be washed have imparted to them a toroidal circulation, the major portion of which follows, in general, a path entirely within the tub 11, as indicated by the arrows 17. A minor portion of the toroidal circulation follows a path indicated by the arrows 18, which includes

2

flow of liquid from the tub 11 through perforations 19 in the lower part of the tub 11, then upwardly through the space 12 between the tubs 11 and 12 and then inwardly through filtering means 20 placed on the inner tub 11 near the top of the tub and at the surface level of the normal charge of liquid in the tubs. The filtering means 20 may take the form of a series of filters removably secured to the tub 11, for example by clamps 21. However, if desired, the filtering means may be one continuous filter around the top of the tub 11 along the zone 15.

Any suitable mechanism may be provided for producing agitation of the liquid and articles to be washed during a washing period and thereafter to rotate the tubs 10 and 11 to produce a rapid, centrifugal drying operation. Merely by way of example, a mechanism such as disclosed in my copending application Serial No. 358,871, filed September 28, 1940, may be used for this purpose. In the embodiment herein illustrated, the tubs are supported on a resilient rubber-like collar 22 which supports a rotatable shaft 23 and a vertically reciprocable shaft 24. The rotatable shaft 23 is secured to the tubs 10 and 11 by means of the hub 25, so that rotation of the shaft 23 produces rotation of the tubs 10 and 11, and preferably also rotation of the agitator 14 at the same rate as the tubs. The vertically reciprocable shaft 24 is secured to the agitator 14, for example by the nut and bolt construction 26. Preferably the shaft 24 is vertically keyed (not shown) with the rotatable shaft 23, so that the shaft 24 may be vertically reciprocated independently of the shaft 23, but is caused to rotate with the shaft 23 when the shaft 23 rotates. A flexible bellows 27 is provided between the agitator 14 and the inner collar 28 of the tub construction, so that the liquid cannot flow down the shaft construction from the tubs. Suitable power mechanism is connected to the shafts 23 and 24 to produce reciprocation and rotation as heretofore described, and such mechanism may, if desired, be of the construction disclosed in my said copending application.

In the operation of the machine, articles to be washed, such as clothes, and washing liquid, such as water and soap, or water alone, may be placed in the tubs to the level 15. The driving mechanism then causes the agitator 14 to reciprocate vertically, while the tubs 10 and 11 are maintained stationary. This agitation produces the toroidal circulation heretofore described, as indicated by the arrows 17 and 18. This produces a washing action on the clothes; but at the same

time tends to produce a scum in the washing liquid. This scum is caught by the current of the toroidal flow and a portion of it is continuously carried by the minor flow indicated by the arrows 18 past the perforations 19 and to the filtering means 20. Here the scum accumulates in a scum arresting zone on the outer surface of the filtering means 20 during the agitation period, so that eventually a very large proportion of the scum accumulates on the filters. Thereafter the driving mechanism stops the vertical reciprocation of the agitator 14 and rapidly rotates the tubs 10 and 11 and the agitator 14. This produces an outward centrifugal flow of liquid through the perforations 19 and the filtering means 20. The liquid then flows over the lip 29 of the outer tub 10, and carries with it a large amount of the scum which accumulated on the outside of the filtering means 20. The outward flow of liquid through the filtering means 20 produces a cleaning action since it tends to remove a large amount of the scum from the filtering means 20, so that it can be carried out over the lip 29 during the centrifugal action. If desired, the filters 20 may be further cleaned of any remaining scum either by brushing them while they are on the tub, or by removing them from the clamps 21 and washing them separately.

I have shown this invention as applied to a washing machine in which the agitating means is movable independently of the tub construction, although it is to be understood that it may be applied to other types of washing machines.

While the form of embodiment of the invention as herein disclosed, constitutes a preferred form, it is to be understood that other forms might be adopted, as may come within the scope of the claims which follow.

The term "scum" as used herein is intended to define any or all of the undesirable substances which tend to circulate with the washing fluid and which, unless removed, tend to deposit on the articles being washed particularly during the drying operation. Such substances include lint which comes from the articles themselves or insoluble particles produced by reaction during the washing operation, and other such undesirable substances.

What is claimed is as follows:

1. In a washing machine, an outer rotatable tub having an overflow level and adapted to retain liquid, an inner rotatable tub having perforations in its lower part, filtering means below said level on the upper part of said inner tub, an agitator causing toroidal circulation of liquid out of said inner tub through said perforations and returning into said inner tub through said filtering means, and means to rotate said tubs centrifugally to cleanse said filtering means by the outward centrifugal flow of liquid from said inner tub through said filtering means.

2. In a washing machine, a rotatable outer tub adapted to retain liquid when stationary and to discharge liquid centrifugally when rotated, an inner rotatable tub within said outer tub, there being a space between said tubs, perforations in said inner tub, filtering means on said inner tub, and agitating means causing circulation of liquid from said inner tub through said perforations into the space between said tubs and from said space through said filtering means into said inner tub, the rotation of said tubs causing outward flow of liquid through said filtering means to clean said filtering means and causing centrifugal discharge of liquid from both of said tubs.

3. In a washing machine, a rotatable outer tub having a centrifugal overflow level and adapted to retain liquid when stationary and to discharge liquid centrifugally when rotated, an inner rotatable tub within said outer tub, there being a space between said tubs, provision for outward flow of liquid from said inner tub to said outer tub below said level, filtering means on said inner tub below said level, and agitating means in said inner rotatable tub causing circulation of liquid from said inner tub through said provision into the space between said tubs and from said space inwardly through said filtering means into said inner tub and means to rotate said tubs to discharge liquid outwardly through said filtering means and out of said outer tub.

4. In a washing machine, a rotatable outer tub having a centrifugal overflow level and adapted to retain liquid when stationary and to discharge liquid centrifugally when rotated, an inner rotatable tub within said outer tub, there being a space between said tubs, an outward flow connection from said inner tub to said outer tub below said level, filtering means on said inner tub below said level, and a vertically reciprocable agitator in said inner tub causing toroidal circulation of liquid below said level from said inner tub through said connection into the space between said tubs and from said space inwardly through said filtering means into said inner tub, and means to rotate said tubs to discharge liquid outwardly and centrifugally through said filtering means and out of said tubs.

5. In a washing machine, an outer rotatable imperforate tub having a centrifugal overflow level, an inner perforate tub secured to rotate with said outer tub and having perforations below said level, a vertically reciprocable agitator in said inner tub, filtering means near the upper part of said inner tub below said level, and means for vertically reciprocating said agitator during an agitating period to cause toroidal circulation of liquid below said level through said perforations and inwardly through said filtering means and for centrifugally rotating said tubs during a centrifuging period to force liquid outwardly through said filtering means and to discharge liquid from said tubs.

6. In a washing machine, an outer rotatable imperforate tub having an overflow level, an inner rotatable tub having perforations below said level, scum filtering means on said inner tub below said level, an agitator causing liquid to flow out of said inner tub outwardly through said perforations and to return to said inner tub through said filtering means, and means to rotate said tubs centrifugally to remove scum from said filtering means by the outward centrifugal flow of liquid from said inner tub.

7. In a washing machine, a rotatable tub having an overflow level and adapted to contain washing liquid and articles to be washed below said level, vertically disposed filtering means below said level and adjacent the outer periphery of said tub, means to circulate said liquid radially outward below and beyond said filtering means and then upwardly and radially inward through said filtering means below said level and to cause agitation of said washing liquid and articles to be washed, and means to rotate said tub and filtering means centrifugally to cleanse said filtering means by the outward centrifugal flow of liquid from said tub through said filtering means.

8. The method of washing articles which com-

prises agitating said articles in a washing fluid held in a confining zone to produce an outward and inward toroidal flow of a major volume of fluid and articles and an outward and inward toroidal flow of greater radius of a minor volume of fluid, filtering scum from said fluid below the top surface of said fluid as it flows inwardly in said minor volume of fluid, and centrifugally discharging from said zone said major and minor volumes of fluid and scum outwardly while arresting outward movement of said articles, the centrifugal discharge of said major and minor volumes of fluid carrying said scum from said zone.

9. The method of washing articles which comprises agitating said articles in a washing fluid held in a confining zone to produce an outward and inward toroidal flow of a major volume of fluid and articles and an outward and inward toroidal flow of greater radius of a minor volume of fluid below the top surface of said fluid, arresting scum from said fluid below said top surface of said fluid in a scum arresting zone as said fluid flows inwardly in said minor volume of fluid, and centrifugally discharging from said zones said major and minor volumes of fluid out-

wardly from said articles while restraining outward movement of said articles and centrifugally discharging scum from said scum arresting zone to dry said articles and disposed of said scum, the centrifugal discharge of said major and minor volumes of fluid carrying said scum from said zone.
